ADHESIVE TAPE DISPENSER

Arthur A. Anderson, Rose Township, Ramsey County, Minn., assignor to Minnesota Mining & Manufacturing Company, St. Paul, Minn., a corporation of Delaware

Application March 17, 1943, Serial No. 479,440

7 Claims. (Cl. 164—49)

This invention relates to dispensers for tape, especially tape that is coated with adhesive, particularly pressure-sensitive adhesive which is normally tacky without the necessity of being activated by solvents or heat.

Objectives include the provision of a device whereby a predetermined length of tape is accurately measured, severed and held in position ready to be applied to a surface.

Broadly, there is disclosed herein a dispenser comprising a feed element having a series of spaced tape feed surfaces to each of which is adapted to adhere an adhesive tape for feeding by revolution of said element, a cutter for cutting the tape fed by said surfaces, and means for moving said cutter to cut said tape as said feed element is revolved to feed said tape.

The feed element may be a wheel, the cutter may be a movable knife, and the means for moving the knife may be a cam which forms a means of connection between the wheel and the knife whereby the knife is moved to cut the tape as the wheel rotates.

In the embodiment illustrated herein, the knives are six in number, located slidably within the wheel and extending radially from the center, their outer ends sharpened to sever the tape that is trained around the wheel's periphery when they are thrust outwardly against it. The cam is located on the wheel's shaft and is shaped to move the knives outwardly and inwardly as the wheel turns, the shaft and cam remaining fixed.

More particularly, the embodiment illustrated herein comprises means for holding a supply roll of tape, a cutter wheel adapted to receive tape from the roll about its periphery, six pairs of fingers disposed about the periphery in spaced relationship, each pair pivotally mounted on the wheel so as to extend across the periphery over the tape when the pair is in closed position and so as to be clear of the periphery when in open position thereby permitting the supply of tape to be introduced into contact with the periphery, the inner edges of the fingers being adapted to form a series of angularly spaced feed surfaces about the wheel when in closed position which grip the tape by adherence thereto, a fixed shaft on which the wheel rotates, a finger cam on the shaft, followers associated with the cam and the fingers whereby rotation of the wheel opens and closes the fingers, six knives slidably held within the wheel and extending radially from the center, their outer ends sharpened so as to sever the tape when they are thrust outwardly against

it, and a knife cam on the shaft whereby the knives are moved outwardly and inwardly as the wheel rotates, thereby severing the tape into successive short lengths as the wheel is revolved, the cut lengths adhering to at least one of the feed surfaces for ready removal therefrom.

The knives and fingers are here shown so positioned in relation to each other that the outward cutting end of each knife extends between the two fingers of each pair thereof when the knife is thrust outwardly through the tape, whereby the fingers serve to hold the tape firmly inwardly against the periphery and thus help the tape resist the knife thrust sufficiently to be severed thereby. The cams here shown are generally of a thrusting type, the knives and fingers which they move being spring-loaded inwardly against them. The illustrated machine is adapted to be power driven. Switching means is provided whereby the machine operates through one dispensing cycle and comes to a stop after having withdrawn, measured, severed and held in dispensing position one piece of tape, all without manual operation or assistance save the pressing of a starter switch to initiate the cycle, so that the device is substantially automatic.

In the accompanying drawings and description the end of the machine at which the operator stands when facing the machine to operate it is called the "front," and the terms "right" and "left" are from the point of view of such operator.

Figure 1 is a perspective view of the machine.

Figure 2 is a right side elevation with the side of the casing broken away.

Figure 3 is a plan view with the upper portion of the casing broken away.

Figure 4 is a vertical cross-section of the machine taken on the line 4—4 in Figure 2 with the casing removed, showing portions of the machine in front elevation.

Figure 5 is a vertical longitudinal section of the machine taken on the line 5—5 in Figure 3 with the casing removed, showing portions of the machine in left side elevation.

Figure 6 is an elevation of the edge or peripheral portion of the wheel with half of the wheel shown in radial axial section taken on the line 6—6 in Figure 2.

Figure 7 is a radial axial section of half of the wheel taken through the longitudinal center of a spoke.

Figures 8 and 9 are vertical sections of the wheel taken on the lines 8—8 and 9—9, respectively, in Figure 6.

Figures 10 and 11 are sectional views of the portion of the wheel at which severed tape may be applied direct to objects, showing objects in the process of being taped.

Figure 12 is a perspective view of a tape and finger guide in position on the end of a spoke.

Figure 13 is a perspective view of a pair of fingers looking upwardly from below toward the tape-gripping surfaces.

Figure 14 is a wiring diagram.

A supply roll R of tape T is carried on the tape roll holder drum 20 which is journaled on a spindle 21 in the upright plate or drum support 22, the latter being fixed to the base 23. The drum is aligned so that the tape T will be properly positioned (in a manner hereinafter described) on the feed wheel (or cutter wheel) 30 as the tape is drawn forward from roll R through the machine. A spool-shaped idle guide roller 24 is rotatably mounted on a suitable shaft or spindle in the upper part of the plate 22 over which the tape may be trained, its adhesive side contacting the roller.

In the present embodiment, the tape T is withdrawn from the supply roll R and propelled through the machine by reason of its temporary adherence to a series of feed surfaces (or tape-gripping elements 31a-31b which are carried by the cutter wheel 30.

Cutter wheel 30 is journaled on a rigid horizontal shaft 29, the latter being fixed in two upright supports 28 and 28'. The wheel comprises a hollow drum-shaped nave 30a whose diameter is about half that of the entire wheel and whose width or axial length is about equal to the thickness of the wheel. Spokes 30b extend radially from the nave, there being six in the presently illustrated machine. Each spoke is relatively thin (Figures 8 and 9) but has a width approximately equal to that of the nave.

Star shaped side-plates 30c and 30d form the sides of the wheel. They are spaced from each other by the width (axial length) of the nave and the spokes, plate 30c being here cast with the nave and spokes in one piece, plate 30d being a separate piece held to the nave by suitable screws 31, and both plates having hubs 30e and 30f, respectively (Figure 6), by which the wheel 30 is journaled on the fixed shaft 29.

Substantially all of the wheel's peripheral surface is formed by segments of sponge rubber 30g placed between the spokes 30b, their inner surfaces adhered or otherwise fastened to the spokes and to the nave 30a, and their outer surfaces approximately flush with the outer end surfaces of the spokes. Opening 30h and slits 30k in each segment increases its yieldability so as to utilize a maximum area of the segment's peripheral surface to press the tape against an object during a taping operation, i. e., when an object is being taped by pressing it inwardly against a tape-covered segment, as shown in Figures 10 and 11.

Thin radial slots 30m (Figure 12) whose width is that of the spokes and nave, extend from the wheel's center through the nave 30a and outwardly through each spoke to the spoke's end along the spoke's approximate longitudinal axis, to accommodate (in each slot) a knife 32, an arm 37c and other parts to be described.

Each knife 32, having a cutting edge x at its outer end is positioned with its inner end contacting the circular cam 29a which is fixed eccentrically on the fixed shaft 29. To each knife is fixed a spring-receiving cup 32a (Figure 9)

which holds the inner end of a spiral spring 33. The outer end is held in a second cup 34 which is inverted in relation to the cup 32a and slidably telescoped therein. The spring is loaded to press

5 the outer end of the cup 34 against the inner wall of the nave 30a thereby holding the knife 32 against the stationary cam 29a at all times. When the wheel 30 turns a knife opposite the cam's lowest point, the knife edge x is slightly 10 "below" or within the outer extremities of the particular spoke 30b within which that knife moves. As the wheel turns, the knife is thrust outwardly by the stationary cam 29a, the edge x being somewhat beyond the ends of the slotted 15 spoke at the outermost point of its thrust so that the tape which lies across the ends of the spoke when trained around the wheel, will be severed by the said outward movement of the knife.

At the end of each spoke 30b is a pair of movable fingers 31-31' whose inner surfaces 31a and 31b, respectively, form the aforesaid feed surfaces or tape-gripping elements which grip the pressure-sensitive adhesive tape by temporary adherence therewith when the tape is trained around the wheel adhesive side out.

20 The lower portion of finger 31' is tapered sharply (Figure 13) so that surface 31b is, in comparison with 31a, extremely narrow (only a few thousandths of an inch in the illustrated machine), the width being such as to permit the finger 31' to hold the tape firmly against the wheel without cutting it but sufficiently narrow to loose its grip on the tape very readily. Finger 31 leads 31' in each pair as the wheel rotates during 25 operation.

Each pair of fingers, when in closed position (see positions I, II, III and IV in the drawings), extends across the wheel's periphery at the ends of the adjacent spoke 30b with the tape between 30 the fingers and the spoke, the tape-gripping surfaces 31a-31b facing inwardly (toward the wheel's center) thereby contacting the adhesive side of the tape. In each pair, finger 31 is sufficiently spaced from finger 31' and properly placed in relation to the adjacent spoke, to permit the adjacent knife 32 to pass freely between the fingers when it is thrust outwardly through the slot 30m in the spoke by cam 29a to sever the tape.

30 Each pair of fingers 31-31' is fixed by a suitable screw 41 to an arm 37c which is pivotally mounted by a pin 35 on the side of the cutter wheel 30. The pin 35 is fixed to the wheel by being pinched or crimped in an annular groove 30i that is turned in the outer surface of side plate 30c. Suitable slots are cut through the "star points" of the plate 30c in register with knife-containing slots 30m in the spokes, to receive the arms 37c, which latter are also partially within the said spoke slots.

35 Each arm 37c and its fingers 31-31', is kept in closed position (Figure 6) by leaf spring 36 which presses the arm 37c about its pivot 35 laterally towards the side plate 30c thereby pressing the tape-gripping surfaces 31a and 31b of the fingers 31-31', respectively, inwardly against the ends of each spoke 30b so that when tape has been trained around the wheel 30 over the ends of the 40 spoke adhesive side up, it will adhere to and be gripped by, the surfaces 31a-31b. The springs 36 are held in place by a disc 38 which overlaps their inner ends and is screwed to the wheel's side plate 30c by screws 42.

45 75 To open the fingers so as to permit fresh tape

to be laid in place along the wheel's periphery, a cam follower 39 is located in each spoke slot 30m between the arm 37c and a fixed cam 29b on the fixed shaft 29. The leaf spring 38 acting through arm 37c which it impels clockwise (Figures 6 and 7) about the pivot 35, presses the follower 39 against the cam 29b at all times. The cam is shaped and positioned so that rotation of the wheel 30 around the fixed shaft 29 will open the fingers a desired distance and close them at desired times during the rotation of the wheel.

Lateral movement of the knife 32 and the follower 39 within each spoke slot 30m is prevented in one direction by the side plate 30c and in the other by a suitable spacer bar 40 which is in the slot between the knife 32 and the side plate 30d.

At the outer end of each spoke 30b a combined tape guide and finger guide is provided in the form of a clip G (Figure 12) which fits over the end of the spoke and extends inwardly on either side of the spoke between the rubber segment 30g and the spoke. The parts of the clip which project outwardly beyond the wheel's periphery form a channel across the periphery to receive the fingers 37-37', and at the same time form a channel lengthwise of the periphery to receive the tape T.

The cutter wheel 30 is rotated by the motor M through a suitable worm gear reduction (not shown) within the gear box 50, the worm wheel shaft 51 transmitting its rotation through pinion 52 to the gear 53, the latter being journaled on the shaft 29, and fixed to the wheel 30 by screws 54 which extend through the side plate 30d into suitable bosses 30j on the nave 30a. The gear and pinion ratio is one to six so that a complete revolution of the power shaft 51 turns the cutter wheel 30 one-sixth of a turn.

A cam boss 51a fixed on the end of worm wheel shaft 51, holds a switch cam 55 by screws 56 which extend through arc-shaped slots 55a in the cam to permit adjustment of the cam in relation to the shaft 51.

The cam is shaped to depress, for a desired period, the spring switch arm 60 which thereupon depresses the actuating pin 61a of a single-pole two-way "micro switch" 61 (a switch wherein a slight downward pressure on the actuating pin will open one electrical contact and close another, and vice versa when the pin is permitted to spring back up upon release of the pressure). Spring arm 60 bears upwardly against the cam 55. The switch is on an upright 62 that it attached to the base 23. Attached to the upright 22 is a well-known two-pole one-way relay 63 whose switches 63b and 63c are normally open, the contacts being closed only when the field coil is energized. A manually operated switch, shown here as foot switch 64 with an actuating pedal 64a contains two single-pole one-way "micro-switches" 64b and 64c (a switch in which an electrical contact is normally open-or-closed except when pressure is maintained on its actuating pin, the pin springing back to normal when pressure is released), one of which is normally open and the other normally closed. Their actuating pins are depressed simultaneously by a single bar 64d which is itself depressed by the pedal 64a.

A suitable casing 70 is attached to the base 23, having an opening 70a through which a portion of the wheel 30 projects to afford access to the lengths of tape that it dispenses, and having a

service shelf 70b at the front end of which articles being taped may be supported.

Mode of operation

5 A supply roll R of pressure-sensitive tape T is mounted on the supply drum 28, positioned so that as the tape is led toward the wheel 30 its adhesive coated side is down. It is led over the idler roller 24 and then threaded around the periphery of wheel 30, adhesive side out, between the fingers 37-37' and the periphery, through the tape channels in the guides G (Figures 3 and 10 12) until the leading end of the tape is even with the spoke which occupies the position indicated in the drawings as position VI. Such threading may conveniently be done by leading the tape from the idler 24 rearwardly and downwardly as far as the spoke in position I, adhering the end temporarily to a convenient surface of the wheel parts there located and then rotating the wheel by the power means until the leading end has followed the rotating wheel around to position VI. The leading portion of the tape between V and VI will then have been automatically severed, and upon removal of this piece the machine is ready for its normal operation.

20 Upon connecting the plug 65 with a suitable source of power (A. C. for the illustrated machine), current flows from one side of the power line to one side of the motor M and to one terminal of the field coil 63a of the relay 63. The other terminal of the coil connects through the normally closed switch 64b in foot switch 64 and through the normally closed contact 61b of cam switch 61 to the other side of the power line. The energized coil 63a thereupon closes the two normally open switches 63b and 63c of relay 63.

25 When the operator then presses the pedal 64a of starting switch 64, its normally closed switch 64b opens but the circuit through the coil remains closed because relay switch 63c is closed. At the same time the normally open switch 64c closes and the motor starts, the circuit then being from one side of the power line to one side of the motor, and from the other side of the power line through closed switches 64c and 63b to the other side of the motor.

30 Switch cam 55, rotated by the motor, is shaped and positioned so as to depress switch arm 60 and thereby the pin 61a of stopping switch 61 almost immediately after the motor starts. The motor then runs independently of the relay and foot switch, the circuit being from one side of the power line to one side of the motor, and from the other side of the power line through the closed contact 61c of cam switch 61 to the other side of the motor.

35 The cam 55 is shaped and positioned on worm wheel shaft 51 in relation to the speed of the motor and to the reduction ratio of the worm gear assembly, so that it will release the switch arm 60 (and thereby open the contact 61c to shut the power off from the motor) at such a point in its rotation that the shaft 51 will coast to a full stop after it has made precisely one revolution. Such release of the switch pin 61a closes contact 61b again and the switching assembly is automatically reset in readiness for the next cycle.

40 If the operator has inadvertently left his foot on the switch pedal 64a, or depressed it a second time before the power is shut off by the cam 55, the shaft will still stop at the end of a cycle in the intended manner, because, whether or not the pedal 64a remains depressed, the opening of 45 61b that occurs early in the cycle shuts off the

power supply from coil 63a whereupon switches 63b and 63c open. Then if the pedal 64a remains depressed, the re-closing of 61b toward the end of the cycle does not energize the coil because 64b is held open by the pedal and the motor remains disconnected from the power source since both the switches 63b and 61c are also open.

Release of the pedal before the start of each new cycle is necessary to enable the assembly to reset itself; but on the other hand once it is started, a cycle will be properly completed and terminated regardless of when the pedal is released as long as the motor is turned far enough in the beginning to close the contact 61c.

The above described rotation of the worm wheel shaft 51 through precisely one full turn which occurs automatically each time the pedal is depressed, turns the gear 53 (through the pinion 52) and thereby the cutter wheel 30 counterclockwise (Figure 2) through 60° of turn, which is referred to herein as "one dispensing cycle."

As a spoke, with its various attachments, approaches the point where the supply of tape from idler 24 first contacts the periphery of wheel 30 (between positions VI and I), the cam follower 39 in said spoke is thrust by the stationary finger cam 29b to the outermost point within its spoke to which it goes at any time, thereby swinging the fingers 37-37' of that spoke (by pressure against their arm 37c) to their most wide open position, as shown in Figure 7. After the tape has been laid in place against the wheel's periphery in the tape-channel in the guide G, the fingers close over it at about the time they reach position I by reason of the shape and position of the fixed cam 29b. Pressure of the spring 36 against the arm 37c presses the fingers 37-37' inwardly against the outwardly facing adhesive coated surface of the tape so that it adheres to the inner surfaces 37a-37b of each of the pairs of fingers that are associated with the spokes in the successive illustrated positions such as I, II, III, IV, whereby rotation of the wheel withdraws the tape from the supply roll and around the wheel to a dispensing station. Adherence of the tape to the leading finger 37 of each pair is much greater than to the trailing finger 37' because the tape-gripping surface 37b on each finger 37' is almost a knife edge (a few thousandths of an inch) compared with the full-width tape-gripping surface 37a of each leading finger 37 (Figure 13). The tape is gripped by both edges of each pair but primarily by the edge or surface 37a, the edge 37b serving primarily to help hold the tape in place during cutting, it being desirable (as described hereafter) that edge 37b will release the tape very readily at the dispensing station.

As the wheel carries a spoke onward from position I toward II, the stationary knife cam 29a gradually thrusts the knife which is held in that particular spoke, outwardly until, at approximately position III, the knife occupies its outermost position, the knife edge x having been thrust clear through the tape while the said tape was being held against the spoke ends on either side of the knife by the fingers 37-37'. The tape is thus severed into successive lengths equal to the peripheral distance from center to center of two adjacent spokes. The leading end of each severed piece is very lightly held by the narrow knife-like inner edge 37b of a finger 37', the trailing end of each severed piece being relatively more firmly held by the inner surface 37a of the finger 37 on the next succeeding spoke.

As a spoke rounds the top of the turn the taper

in stationary finger cam 29b begins very gradually to press the follower 39 outwardly so that at position V the fingers 37-37' are slightly loosened. At VI they are partially withdrawn from full closed position, but due to the said lightness of the adhesive contact with the narrow knife-like edge 37b, the severed piece T-1 lying between positions V and VI remains in its place on the wheel's periphery, the edge 37b releasing it as soon as the finger 37' is moved outwardly and sidewardly away. The natural stiffness or inertia of the tape plus a slight lateral pressure of the guide G against the side of the tape, and possibly other factors, apparently supply the tape with sufficient resistance to the light adhesive contact of edge 37b to break away when finger 37' is removed.

When it is thus in the space on the wheel's periphery between V and VI, the severed piece T-1 is in dispensing position, removably held by its adhesive contact with the inner surface 37a of the finger 37 that is at position V, the said finger, as stated above, being slightly loosened or raised from the end of the spoke beneath it, thereby facilitating ready removal by a slight pull on the severed piece. It may be removed manually by the operator or by a mechanical instrument and be applied to an object; or an object may be taped by pressing such object inwardly towards the wheel's center against the upturned adhesive face of the piece. In Figure 10 a box B is shown being taped in this manner. In Figure 11 a rod, wire, pencil, flower stem or other similar object is shown being taped, e. g., for labelling purposes, as by printed tape.

The dispenser remains motionless with the piece T-1 exposed at the dispensing station as shown in Figures 1 and 2 until, after removal of T-1, the operator chooses to press the pedal 64a whereupon the machine will automatically go through the next cycle and stop again after the wheel 30 has turned the piece T-2 around to the position now shown as occupied by piece T-1.

The present invention provides a novel species of tape dispenser, as defined in the claims herein-after, of the class broadly described and claimed in my co-pending application Serial No. 400,143 filed June 27, 1941.

I claim:

1. A tape dispenser comprising a rotatable cutter wheel adapted to receive adhesive tape about its periphery, a plurality of movable cutting blades mounted on the wheel and underlying the tape-receiving periphery, tape gripping means mounted on and attached to the wheel adjacent to the severing blades to facilitate cutting the tape and adapted to releasably grip adhesive tape and to removably hold cut pieces of tape, the said tape gripping means being adapted to hold the tape independently of any means outside and apart from the wheel means for rotating the wheel and means for successively moving the cutting blades against the tape to cut it when brought to a predetermined position by rotation of the wheel.

2. A tape dispenser comprising means for holding a supply roll of tape, a cutter wheel adapted to receive tape from the roll about its periphery, a plurality of fingers disposed about the periphery in spaced relationship pivotally mounted on the wheel so as to extend across the periphery over the tape when in closed position and so as to be clear of the periphery when in open position thereby permitting the supply of tape to be introduced into contact with the periphery, the

inner edges of the fingers being adapted to form a series of tape gripping surfaces about the wheel when in closed position, a fixed shaft on which the wheel rotates, a finger cam on the shaft, followers associated with the cam and the fingers whereby rotation of the wheel opens and closes the fingers, a plurality of knives slidably held within the wheel and extending radially from the center, their outer ends sharpened so as to sever the tape when they are thrust outwardly against it, and a knife cam on the shaft whereby the knives are moved outwardly and inwardly as the wheel rotates, thereby severing the tape into successive short lengths as the wheel is revolved, the cut lengths held by at least one of the tape gripping surfaces for ready removal therefrom.

3. The device of claim 2 in which the fingers are disposed in pairs with the fingers of each pair, when in closed position, contacting the tape in both directions from the point where the tape is to be cut so as to help the tape resist the outward thrust of the knife sufficiently to permit the knife to sever the tape.

4. The device of claim 2 in which the cams are designed to move the followers and the knives outwardly at desired times by a thrusting movement, with spring means for the return movement.

5. A tape dispenser comprising means for holding a supply roll of tape, a cutter wheel adapted to receive tape from the roll about its periphery, a plurality of pairs of fingers disposed about the periphery in spaced relationship, each pair pivotally mounted on the wheel so as to extend across the periphery over the tape when in closed position and so as to be clear of the periphery when in open position thereby permitting the supply of tape to be introduced into contact with

the periphery, the inner edges of the fingers being adapted to form a series of tape gripping surfaces about the wheel when in closed position, the fingers of each pair, when in closed position, 5 contacting the tape in both directions from the point where the tape is to be cut so as to help the tape resist the outward thrust of the knife sufficiently to permit the knife to sever the tape, a fixed shaft on which the wheel rotates, a finger cam on the shaft, followers and spring means associated with the cam and the fingers whereby rotation of the wheel opens and closes the fingers, a plurality of knives slidably held within the wheel and extending radially from the center, their outer ends sharpened so as to sever the tape 10 when they are thrust outwardly against it, and a knife cam on the shaft and spring means whereby the knives are moved outwardly and inwardly as the wheel rotates, thereby severing the tape into successive short lengths as the wheel is revolved, the cut lengths held by at least one of the tape-gripping surfaces for ready removal therefrom.

6. A dispenser for pressure-sensitive adhesive tape, including a revolvable feed means having a 15 series of spaced tape feed elements to each of which tape is adapted to adhere by adhesive contact for feeding by revolution of said means, at least one movable cutting blade mounted on the feed means and underlying the tape when the latter is trained around the feed means, and automatic means for moving the blade to cut the tape as the feed means is revolved to feed the tape.

7. The device of claim 6 in which there are a 20 plurality of movable cutting blades.

ARTHUR A. ANDERSON.
